UNITED STATES PATENT OFFICE.

CHARLES A. BRAWN, OF PHILADELPHIA, PENNSYLVANIA.

LOADING DEVICE.

1,336,674.

Specification of Letters Patent. Patented Apr. 13, 1920.

Application filed June 7, 1918. Serial No. 238,637.

To all whom it may concern:

Be it known that I, CHARLES A. BRAWN, a citizen of the United States, residing at Philadelphia, in the county of Philadelphia and State of Pennsylvania, have invented 5 certain new and useful Improvements in Loading Devices, of which the following is a specification.

It is usually the custom in loading large 10 and deep drilled rock holes with dynamite or other explosive material for blasting purposes, to successively drop by hand sticks or pieces of dynamite into the holes until a sufficient charge has accumulated to properly blast the rock. To do this it is necessary 15 for a man to remain close to the hole and listen so that he can determine whether the dynamite has fallen completely to the bottom of the hole since sometimes the sticks 20 of dynamite become jammed within the hole before they have reached the bottom. When this occurs it is necessary to probe the dynamite so that it will fall to its proper position, either to the bottom of the hole or upon 25 the top of the piece of dynamite which has been previously dropped.

It is perhaps unnecessary to state that it is extremely dangerous to load these drilled holes in this manner and horrible accidents, 30 resulting in death and disfigurement to the workmen, have often occurred.

Furthermore, this previous method of loading drilled holes was extremely slow since in 35 large blasting operations the holes are often drilled to the extent of one hundred and fifty feet or more and thereby requires a great deal of time to load, and also, if they are not loaded in a reasonable time the dynamite becomes damp and does not explode 40 properly.

In addition to the above facts, it is necessary when loading a drilled hole by the old method, to have a large quantity of the dynamite in positions immediately surrounding 45 the hole and sometimes this is exploded by accident, the result of which is likewise dangerous.

One object of my invention is to provide 50 means whereby drilled holes can be quickly and safely filled with a charge of dynamite or other explosive material.

Another object is to so construct the device of my invention that it can be operated by a man located at a safe distance from

the hole and so that the man is able to listen 55 and distinguish whether or not each successively dropped piece of explosive material has reached its proper destination.

A still further object is to so construct my improved loading device that there is practically no possibility of the successive pieces 60 of explosive material to jam within the drilled hole.

Another object is to so make my improved device that it will be of simple construction, 65 durable, and can be operated by one man.

These objects, and other advantageous ends which will be described hereinafter, I attain in the following manner, reference being had to the accompanying drawings in 70 which—

Figure 1 is a side elevation of my invention, showing a door of a magazine open so as to reveal a number of pieces of dynamite or other explosive material,

Fig. 2 is a central sectional elevation of 75 my invention, looking in the same direction as shown in Fig. 1,

Fig. 3 is an enlarged fragmentary section of a portion of my invention,

Fig. 4 is a section taken on the line 4—4 of Fig. 3,

Fig. 5 is a section taken on the line 5—5 of Fig. 3,

Fig. 6 is a section taken on the line 6—6 85 of Fig. 3,

Fig. 7 is a perspective view of a base forming a part of my invention,

Fig. 8 is a perspective view of a magazine for the explosive material and showing all 90 the parts thereof in a "set" position which they will occupy when loaded with explosive material and ready to be inserted within the base shown in Fig. 7, and

Fig. 9 is a fragmentary rear elevation of 95 the magazine.

Referring to the drawings, 10 represents a base which is preferably made of wood and has a depending cylindrical sleeve 11 and a flange plate 12. The sleeve 11 is designed to be inserted within the drilled hole 13 of the rock, as clearly shown in Figs. 1 and 2, and so that the flange plate 12 of greater area than the diameter of the hole 13, rests on the upper surface of the rock. 105 The base 10 also includes a box 14 which is in straight alignment with the axis of the sleeve 11.

This box 14 has a hole 15 extending throughout its entire height and which communicates with the interior of the sleeve 11, as clearly shown in Figs. 1 and 3. The upper portions of the hole 15 is rectangular in cross section, as clearly shown at 16 in Fig. 6, to form a receptacle for a magazine 17. The receptacle 16 terminates at its bottom in a shoulder 18 which serves as an abutment and rest to limit the downward movement of the magazine within the receptacle. From the shoulder 18 the hole 15 is circular in cross section, as shown at 19, and tapers downwardly from a greater diameter than the internal diameter of the sleeve 11 to a diameter equal to the diameter of the interior of the sleeve 11 so that the portion 19 of the hole smoothly blends with the internal diameter of the sleeve 11.

20 The box 14 has a lateral extension 20 illustrated in the form of a box having a duct 21 extending therethrough at an incline. This duct is also extended through the box 14 and communicates with the hole 15.

25 The bottom of the magazine 17 has an aperture 22 which, when the magazine is positioned within the receptacle 16, registers with the duct 21, the magazine being hollow and open at its bottom so that the duct 21 is 30 in communication with the interior of the magazine and also with the hole 15 below the shoulder 18.

A hose 23 has one end inserted within the duct 21 in the extension 20 and this hose 35 can be extended to any desired length so that a person holding the opposite end of the hose to the ear can hear sounds made within the drilled hole 13 in the rock, in a manner hereinafter more fully described.

40 The magazine 17 in the form illustrated, is made in the form of a box which is rectangular in cross section so that its lower end portion 24 fits within the receptacle 16. The interior of the end portion 24 of the 45 magazine 17 is circular in cross section, as illustrated in Fig. 6, and the uppermost portion is, by preference, rectangular in cross section.

The rear 25 of the magazine has a series 50 of openings 26 therein, one located above another. Within these openings are pivoted a number of floors 27, said pivoting in the present instance being done by hinges 28 (see Figs. 3, 8, and 9). These floors 27 are 55 adapted to swing within the magazine so that they can be positioned transversely thereof to form supports for sticks or pieces 30 of dynamite or other explosive material. These floors are retained in their transverse 60 or supporting positions by means of a series of pins 31 having eyelets 32 at their outer ends through which are connected a flexible cord or rope 33.

Perforations 34 are formed in the front 65 35 of the magazine so that these pins 31 can

be projected from the outside through the perforations 34 and under the respective floors 27 to hold them in said transverse position, as shown at the top portion of the magazine illustrated in Figs. 2 and 3, the 70 cord 33 and its attaching eyelets 32 remaining on the outside of the magazine. The upper end of the cord 33 is secured directly to the magazine and the other end of the cord can be made of any length to permit it 75 to be pulled by a person located at a safe distance from the drilled hole 13.

The magazine is provided at one side with a door 36 so that after the floors have been moved into their transverse positions and supported by the pins 31, the pieces 30 of explosive material can be placed upon the several floors and the magazine can then be carried while in the position shown in Fig. 8, to the base 10, as shown in Fig. 7, 80 85 and set therein, as shown in Figs. 1 to 3, inclusive. After the magazine has been so positioned the operator at a safe position places the remote end of the hose or tube 23 to his ear and pulls or jerks upon the cord 33. This action causes the lowermost pin 31 to be withdrawn from the magazine and in so doing the weight of the explosive material upon the lowermost floor 27 will cause said floor to swing on its pivot and the 90 lowermost piece of explosive material will fall first through the end portion 24 of the magazine, then through the portion 19 of the hole 15 into the sleeve 11, and finally into the drilled rock hole 13. The operator 100 then waits until he hears the thud caused by the explosive material striking the bottom of the hole and then again pulls the cord 33 to cause the next pin 31 of the series 105 to be removed from the magazine to release the second piece of explosive material, and so on until the magazine has been emptied of its entire charge.

While this operation has been taking place, another magazine can be filled by another person and the empty magazine can be replaced by the full one. Thus the drilled hole can be quickly and safely filled with explosive material by a person located at a safe distance from the drilled hole.

110 While the weight of the pieces of explosive material is sufficient to cause the floors to drop when the supporting pins are released, I preferably provide coiled tension springs 37, the opposite ends of which are 115 respectively connected to the rear 25 of the magazine 17 and to angularly disposed end pieces 38 on the several floors. These springs not only cause the floors 27 to 120 quickly drop but also prevent "back lash" or rebounding movement which might otherwise occur and jam the explosive material within the magazine.

I also provide clasps or latches 39 to hold the door 36 in a closed position after the 130

magazine has been filled and for sake of convenience in opening the door I provide the latter with a knob 40.

It will be noted that the internal diameter 5 of the end portion 24 of the magazine 17 is less than the internal diameter of the upper part of the portion 19 of the hole 15 so that the pieces of explosive material, while falling, will meet with no obstructions in passing 10 from the magazine into the portion 19 of the hole 15 or into the sleeve 11. Further than this, the interior of the magazine, when positioned within the base 10, is in direct alinement with the hole 15, sleeve 11, and 15 drilled hole 13 so that the pieces of explosive material will fall centrally within the drilled hole 13 and there is practically no chance of becoming jammed. Thus explosive material is dropped accurately into 20 the drilled holes which it is impossible to always do by hand.

I wish it distinctly understood that in making this device no material should be used in its construction which is liable to 25 cause sparks by friction and warn any person making this device that no material other than brass or the like can be safely employed. Even the screws for holding the 30 hinges and the other securing parts should be made, for example, of brass and not of steel or iron.

While I have described my invention as taking a particular form, it will be understood that the various parts of my invention 35 may be changed without departing from the spirit thereof, and hence I do not limit myself to the precise construction set forth, but consider that I am at liberty to make such changes and alterations as fairly come 40 within the scope of the appended claims.

Having thus described my invention, what I claim as new and desire to secure by Letters Patent is:

1. A magazine for containing explosive 45 material and adapted to have its lower end inserted within a hole in the ground; means secured to said magazine and designed to engage the top of the ground, whereby the length of said magazine entering said hole 50 will be limited and a structure is provided to assist in holding the magazine in an upright position; and means operative to release said explosive material to permit it to drop into said hole; substantially as described.

55 2. A device of the character described including a supporting structure adapted to support explosive material and to be placed over a hole in the ground; and means for releasing said material, said means having an actuating portion extending laterally to a 60 position sufficiently distinct from said explosive material to permit a person to safely operate said releasing means to cause the explosive material to drop into said hole; substantially as described.

3. A device of the character described including a supporting structure adapted to support explosive material and to be placed over a hole in the ground; means for releasing said material, said means having an 70 actuating portion extending laterally to a position sufficiently distinct from said explosive material to permit a person to safely operate said releasing means to cause the explosive material to drop into said hole; and 75 sound conducting means communicating with the hole; substantially as described.

4. A magazine adapted to be positioned over a hole; means for releasing explosive material contained in said magazine to permit it to drop into said hole; and sound transmitting means in communication with said hole and extending to a position remote from said hole whereby the sound produced by the stopping of said explosive material, 80 after passing within the hole, can be heard, substantially as described.

5. A magazine adapted to be positioned over a hole; movably mounted floors positioned one above another within the height 90 of said magazine; means for normally holding said floors in positions to respectively support pieces of explosive material; and means for releasing said floors whereby said pieces of explosive material are successively 95 permitted to fall through said magazine into said hole, substantially as described.

6. A magazine adapted to be positioned over a hole; movably mounted floors positioned one above another within the height 100 of said magazine; members for respectively holding said floors in positions to support pieces of explosive material; and means for moving said members out of holding engagement with the floors to permit said 105 pieces of explosive material to successively fall through the magazine into said hole, substantially as described.

7. A magazine adapted to be positioned over a hole; movably mounted floors positioned one above another within the height 110 of said magazine; a series of members for respectively holding said floors in positions to support pieces of explosive material; and a cord connected to said members whereby, 115 when the cord is periodically pulled, the members will be periodically moved out of holding engagement with the floors to permit said pieces of explosive material to fall through the magazine into the hole, substantially as described.

8. A magazine adapted to be positioned over a hole and having a plurality of superimposed apertures therein; floors movably mounted within said apertures and adapted 125 to be moved transversely to the height of said magazine; means for holding said floors in their transverse positions whereby the floors can be used to support pieces of explosive material within the magazine; and 130

means for actuating said floor-holding means whereby the floors can be released to cause said pieces of explosive material to fall through said magazine into the hole, 5 substantially as described.

9. A magazine adapted to be positioned over a hole and having a plurality of superimposed apertures therein; floors movably mounted within said apertures and adapted 10 to be moved transversely to the height of said magazine; means for holding said floors in their transverse positions whereby the floors can be used to support pieces of explosive material within the magazine; 15 means for actuating said floor holding means whereby the floors can be released to cause said pieces of explosive material to fall through said magazine into the hole; and means for holding said floors after being 20 released to prevent said floors from rebounding into a transverse position, substantially as described.

10. A magazine adapted to be positioned over a hole; movably mounted floors positioned one above another within the height 25 of said magazine; means for normally holding said floors in positions to respectively support pieces of explosive material; and means for releasing said floors whereby said 30 pieces of explosive material are successively permitted to fall through said magazine into said hole, said magazine including a door which, when open, reveals said floors and permits the pieces of explosive material 35 to be readily positioned on said floors, substantially as described.

11. A device adapted to load explosive material into a hole and comprising a base having a box adapted to be positioned over 40 said hole, said box having a hole in alignment with said first hole and throughout a portion of its length providing a receptacle; a magazine adapted to freely fit within said receptacle; and means for releasing explosive 45 material from said magazine to permit it to fall through said hole in the base into said first hole, substantially as described.

12. A device adapted to load explosive material into a hole and comprising a base 50 having a box adapted to be positioned over said hole, said box having a hole in alignment with said first hole and throughout a

portion of its length providing a receptacle and a magazine adapted to freely fit within 55 said receptacle; means for releasing explosive material from said magazine to permit it to fall through said hole in the base into said first hole, said base having a duct therein communicating with said holes; and a hose having one end positioned within 60 said duct and its opposite end extending to a position remote from said hole, substantially as described.

13. A device adapted to load explosive material into a hole and comprising a base 65 having a box adapted to be positioned over said hole, said box having a hole in alignment with said first hole and throughout a portion of its length providing a receptacle and a magazine adapted to freely fit within 70 said receptacle; and means for releasing explosive material from said magazine to permit it to fall through said hole in the base into said first hole, said receptacle terminating at its bottom to provide a shoulder 75 which forms a rest for the bottom of the magazine, the internal diameter of the bottom of the magazine being less than the internal diameter of the hole in the base immediately below said bottom of the magazine whereby a free passage is provided for the explosive material in passing through said magazine into the hole in the base, substantially as described.

14. A device adapted to load explosive 85 material into a hole and comprising a base having a box adapted to be positioned over said hole, said box having a hole in alignment with said first hole and throughout a portion of its length providing a receptacle 90 and a magazine adapted to freely fit within said receptacle; and means for releasing explosive material from said magazine to permit it to fall through said hole in the base into said first hole, said base including a 95 sleeve adapted to be positioned within said first hole, substantially as described.

In testimony whereof I have signed my name to this specification in the presence of two subscribing witnesses.

CHARLES A. BRAWN.
